UNITED STATES PATENT OFFICE.

HARRY H. REED, OF WINTHROP, MASSACHUSETTS.

REFRIGERATOR.

1,383,235.

Specification of Letters Patent. Patented June 28, 1921.

Application filed April 14, 1921. Serial No. 461,297.

To all whom it may concern:

Be it known that I, HARRY H. REED, a citizen of the United States, and resident of Winthrop, county of Suffolk, State of Massachusetts, have invented an Improvement in Refrigerators, of which the following description, in connection with the accompanying drawing, is a specification, like characters on the drawing representing like parts.

10 This invention relates to refrigerators and especially to refrigerators in which the walls are made of suitable insulating material covered on one or both sides with cement, plaster, mastic or the like, such refrigerators being commonly referred to as cement finish refrigerators. The method now commonly employed in building such refrigerators is to build the refrigerator of the desired size in the form of a permanent structure. One difficulty which is encountered with a permanent refrigerator of this type is that of enlarging, changing or removing refrigerators in case necessity requires such action. Where the refrigerator walls are built as a permanent structure the only way to make a change in the refrigerator, either in the way of enlarging it or of removing it, is to bear down the structure and this, of course, results in a total loss of a portion of the structure which is torn down.

25 It is one of the objects of my present invention to provide a cement finish refrigerator which is made in sections that are detachably connected so that by assembling the proper number of sections a refrigerator of any desired size can be produced.

30 The advantage of this construction is that with the sectional structure it is a simple matter to enlarge the refrigerator by adding additional sections, and it is also an easy matter to move the refrigerator by simply disconnecting the various sections and moving the sections individually into the new location where they may be readily set up again to form a complete refrigerator.

35 Other objects of the invention are to provide for detachably connecting the sections together, and to provide sections which are so constructed that they can be handled without danger of chipping or breaking the plaster, cement or other finish, and otherwise to improve refrigerators of this type all as will be more fully hereinafter set forth.

40 In order to give an understanding of my invention I have illustrated in the drawings

a selected embodiment thereof which will now be described after which the novel features will be pointed out in the appended claims.

Figure 1 is a side view of a refrigerator embodying my invention.

Fig. 2 is a section on substantially the line 2—2, Fig. 1.

Fig. 3 is a fragmentary section on the line 3—3, Fig. 1.

Fig. 4 is a fragmentary section on the line 4—4, Fig. 1.

Fig. 5 is a perspective view of one of the wall sections.

A refrigerator embodying my invention may be made of any number of sections or units depending on the size required. In the drawings I have illustrated a refrigerator in which two opposite side walls are each made of three sections or units connected together, in which the end walls are made of two sections or units and in which the ceiling and floor are each made of three connected sections or units. In the drawings 1 indicates generally the refrigerator and the sections on one side are indicated at 2, 3 and 4 while those on the opposite side are indicated at 5. The two sections in each end wall are indicated at 6. The sections of which the floor is composed are indicated at 7 and those of the ceiling are indicated at 8. Each section comprises a unit complete in itself which can be detached from other sections and moved bodily from one location to another. In the drawings the section 3 in one wall is shown as having a door 9 for the introduction of ice and the section 4 is shown as having a door 10 to afford entrance to the refrigerator room.

45 Each unit section of the refrigerator comprises a skeleton framework preferably of wood, a filling of insulating material filling the framework, and a layer of coating of plaster, cement, plastic or other similar finishing material on one or both sides of the unit.

50 In the section 2, for instance, the wooden skeleton comprises two posts 11 and 12 at one vertical edge of the unit, a post 13 at the opposite edge, two cross pieces 14 and 15 at the top connecting the posts, and similar cross pieces 16 and 17 at the bottom also connecting the posts. These posts 11 and 12 and also the cross pieces are placed one behind the other and in a stepped relation as shown. The space within the skeleton

frame is filled by suitable insulation 18 and this insulation may be in the form of slabs of cork board or slabs of any other insulating material or may be even in the form of 5 loose granular cork or similar insulating material. If slabs of cork board or similar insulating material are used the slabs will be cut to the proper shape to fit within the skeleton frame and may be secured to the 10 frame in any suitable or usual way. Such slabs will preferably be arranged so that the faces thereof will come flush with the sides of the skeleton frame. In the drawings I have shown the body of each unit as 15 formed from two slabs of insulating material, and where two posts or cross members are used at each edge of the frame I will preferably employ posts or cross members having a thickness equal to that of the slabs. 20 The post 13 is shown as having a thickness equal to two slabs. With this arrangement the outer slab 18 will overlie the post 7 and cross member 15.

The outer surface of the unit 2 is covered 25 with a layer 19 of plaster, cement, plastic or similar finishing material and the inner face of the unit is covered by a similar finished coating 20. If the insulating material 18 is of the proper character, such for instance as cork board, the plaster coating 19, 20 may be applied directly to the cork board. If desired, however, suitable metal lathing may be secured to the cork board before the plaster is applied thereby to assist in holding 30 the plaster in place. I have herein shown metal protecting strips 21 which inclose the edge of the plaster coating and serve as a protection therefor. These metal strips are nailed or otherwise secured to the skeleton 35 framework before the plaster is applied and when the plaster has set the plastered area is circumscribed by the metal protecting strips which prevents danger of the plaster chipping or breaking at the edge.

40 Each of the units is made up in substantially this way except that the sections are so constructed that the vertical edges of the skeleton frame which form joints in the walls will be of a double width similar to 45 the post 13. At the sides of the units which meet at the corners and at other places I will preferably use the frame having the two overlapping members to form the stepped structure shown at 14, 15, 16 and 17.

50 The floor of the refrigerator is also made in sections, each section comprising a skeleton framework and a suitable filling. The skeleton framework of the floor comprises the members 22, 23 at one side having the 55 overlapping relation and the members 24, 25 at the other side, said framework being filled up by the cork board 18 or other insulating material. On top of the cork board is a layer 95 forming a concrete base and 60 then on top of this a cement layer 26 form-

ing a finishing layer or working floor. 27 indicates a wooden member which borders the outside of the layer 25, 26. The outer edges of the base sections have the stepped formation provided by the members 22, 23, 70 27. The edges of the base sections which meet each other are made vertical so that the sections have an abutting relation. In Fig. 3 the floor section at the left hand end is shown as having a wooden member 29 extending from one end to the other and the adjacent floor section is shown as having angle iron 30 embedded therein which angle iron abuts the wooden member 29. If desired, the angle iron may be used on both 80 sections or both sections may have the wooden member 29, the important thing being that each section has a wall which meets and abuts the wall of the adjacent section. 85 The concrete base 95 and cement layer 26 may be laid on the sections individually or may be laid after the sections have been assembled in which case the floor of the entire refrigerator will be laid at one operation. In laying the cement or concrete floor the 90 parting members 29 and 30 will act as separators between the cement base 95 of one section and the concrete base of the next adjacent section. In laying the floor I propose to use a thin sheet metal parting strip 95 99 directly at the joint between the sections, said parting strip acting as a separator between the cement layer 26 of one section and that of the next adjacent section. This parting strip does not come clear to the top 100 of the cement layer and after the latter is laid and before it is set a V groove 31 will be formed directly over the parting strip 99. On the other hand if the floor sections are completely built, each with its concrete 105 base 95 and cement layer 26 before the sections are assembled then each concrete layer will be formed with the beveled edge corresponding to the inclined grooves 31.

The various wall sections and ceiling sections are each made independently. 110

In building a refrigerator the floor sections 7 are first assembled and laid in proper relative position, and if such floor sections are originally built without the concrete base 115 95 and cement layer 26, such concrete base and cement layer will be laid on the assembled floor sections, but will be laid in such a way that the concrete base for each section is separated from that of the adjacent sections by the parting strips 29, 30 and 99. The floor portion of the refrigerator room which is thus made by the assembling of the various floor sections, will have a stepped formation at its periphery which 120 is produced by the relative position of the members 22, 23 and 27. The lower edge of each wall section also has the stepped formation provided by the members 16 and 17 and the vertical edges of the wall sections 125 130

which meet at the corners have the stepped formation provided by the posts 11 and 12. After the floor has been laid the wall sections are put in position and the stepped formation at the bottom of each wall section fits the stepped edge of the floor section as shown clearly in Fig. 3. The walls may be connected to the floor sections by means of lag screws 33 or other similar fastening devices which are screwed into the overlapping skeleton frame. I will preferably place packing material indicated at 34 between the meeting faces of the wall sections and base sections, this packing material having a proper construction to form a water tight joint when the wall and floor sections are firmly connected. When the wall sections have been erected the top sections 8 are placed in position. The top edges 20 of the wall sections have the stepped formation provided by the overlapping members 14, 15. The top sections are made in a manner similar to that described so that each presents at its outer edge the skeleton frame 25 presenting the stepped surface formed by the frame members at 35, 36. These top sections are laid on the wall sections so that the stepped portion thereof fits the stepped portion at the upper edge of the wall sections and the top and wall sections may be 30 then screwed together by suitable means such as lag screws 33. A packing or gasket 34 will also preferably be used at the joint. Similarly a packing 36 will be used between 35 the meeting vertical edges of the wall sections, and if desired, the vertical members 13 of the frame may be grooved, as shown at 37 so that a key or spline may be used for holding the two wall sections in line with 40 each other.

After the structure has thus been built up then the corners and joints are finished preferably by applying angle-shaped finishing members to the corners and other finishing members to the vertical joints in the walls.

These finishing members may be made of iron, wood or wood faced with sheet metal. At the vertical corners between the side 50 walls I employ a finishing member 87 of angle shape which incloses the corner and the legs of which are secured thereto by suitable screws 38. At the corner around the top of the refrigerator I employ an angle 55 finishing member 39 which also incloses the corner and is secured in place by suitable screws 40. Before the angle finishing members 87 and 39 are put in place I will secure to the walls filling strips 43, 44, 45 which 60 are of a thickness equal to that of the plaster coating 19 and which bring the surface of the wall flush with the plaster. Similarly, I propose to employ the filling strips 79 and 80 at the top of the side walls and on the 65 ceiling respectively so as to make a flat sur-

face to which the finishing member 39 is secured. Both of these finishing members 87 and 39 are of such dimensions that they cover the filling strips and also overlie the metal protecting strips 21 on the edge of the 70 plaster. These protecting strips prevent the filling strips from injuring or marring the plaster in any way. At the vertical joints between the wall sections at the side of the wall I propose to use finishing strips in the 75 way of plates 41 which may be either of metal or wood as desired. Before these plates are put in position, filling strips 78 will be nailed to the post 13, which filling strips have a thickness equal to that of the 80 plaster 19 and thus form a solid support for the finishing plate 41. This plate 41 is of sufficient dimension to overlie the protecting strips 21 as shown in Fig. 4. If desired the plate 41 may have a web or fin 77 extending 85 therefrom and entering a slot between the adjacent wall sections. This finishing plate 41 may be secured in place by screws or any other suitable means. For finishing the inside of the refrigerator I propose to use 90 angle shaped finishing strips 46 at the corner between the walls and the floor and also at the corner between the walls and the ceiling. These angle shaped finishing strips may be either of metal or wood and in the 95 case of the finishing strip at the floor I propose to use a filling strip 47 to which the finishing member 46 is secured. The finishing member has the proper size to overlie the metal protecting strips 21 at the edge 100 and the plaster as above described. The finishing strip 46 at the corner and the walls and ceiling is supported on filling strips 48 and is of a size to overlie the metal protecting strips 21 on the plaster coating. 105

These finishing strips 39, 87 and 46 serve to give a proper finish to the corners of the structure and they may also function as tie members for assisting in holding the various sections together.

At the bottom of the refrigerator I propose to employ a finish strip 49 which may be of either wood or metal and the upper edge of which overlies the protecting strip 21 at the bottom of the plaster. This 115 finished strip 49 may be provided with a web 50 which occupies a slot between the floor section and the wall section.

At the vertical inside corners angle shaped finishing members 69 are used which may be either of wood or metal and which is secured to filling strips 68, said finished member 69 having sufficient dimensions so that its edges overlie the metal protecting strips 21 on the edges of the plaster. The vertical 120 joints between the wall sections at the inside of the refrigerator are finished by a finish strip 45 which is secured to filling strips 65 and which overlies the protecting strips 21 at the edges of the plaster. 125 130

A refrigerator having the above construction is just as effective for use as a so-called cement finish refrigerator built as a permanent structure, but it has a further advantage that if it is desired to enlarge the refrigerator by extending it in any direction the sections can be readily disconnected and new sections added to make a refrigerator of the desired size. Further, if, for any reason, it is desired to move the refrigerator into a new location, said refrigerator can be readily taken down and the sections moved independently to the new location and then they may be assembled again to make a complete structure. The taking down of the refrigerator involves simply removing the corner strips 46, 87, 39 and 69 and the finish strip 49, and removing the lag screws 33. When this has been done the sections can be separated and moved to a new location and then assembled as above described.

When the floor sections are separated the cement working floor 26 will part along the joint without being broken or chipped so that the floor sections can be readily reassembled again. When they are thus reassembled it will be advisable to fill the V grooves formed in the floor with grouting or cement 32 in order to provide a water tight joint.

The above construction has the further advantage that it will allow of any necessary expansion or contraction without danger of cracking the plaster, cement or other finish. Since the plastic finish is made in sections which are separate from each other each section is capable of having a sufficient movement relative to other sections to accommodate for any expansion or contraction. The use of the metal protecting strips 21 is advantageous because it prevents the danger of the finished coating being chipped or broken when the sections are being assembled or disassembled. In the above description I have used the term "refrigerator" in its generic sense as including any room or compartment which is cooled either by ice or mechanical refrigeration. It will be understood, of course, that if the structure is one in which the cooling is effected by mechanical refrigeration then it will not be necessary to build it with the door 9 to receive the ice.

In the above description and in the following claims I have also used the words "cement, plaster and the like" in a generic sense as covering any suitable plastic material which may be used for the inside or outside coating of the refrigerator and which is applied in plastic form and then is allowed to set or become hard.

While I have herein illustrated one way

of constructing the sections so that they may be assembled yet I do not wish to be limited to the exact structural features shown.

65

I claim.

1. In a concrete finish refrigerator, the combination with a plurality of wall sections each comprising a skeleton framework filled with insulating material and covered on one or both sides with concrete, plaster, mastic or the like, and means for detachably connecting the wall sections together to form a completed wall.

2. In a sectional cement finish refrigerator, the combination with a floor portion, of a wall made in individual sections each comprising a skeleton framework, a filling of insulating material and a coating of plastic material on one or both sides, a roof or ceiling supported by said walls and angle iron finish members inclosing the corner formed by the ceiling and walls and operating to secure the wall sections together.

3. In a refrigerator, the combination with a floor portion having a stepped formation at its edge, of a wall made in separable sections, the lower edge of each presenting a stepped formation to fit the stepped formation of the floor, each section comprising a skeleton framework, a filling of insulating material and a coating of plastic material on one or both faces, and a ceiling supported on said walls and detachably secured thereto.

4. In a cement finish refrigerator, the combination with a plurality of wall sections each comprising a skeleton framework filled with insulating material and provided with a coating of cement, plaster or the like, a metal protecting strip inclosing the edges and the plaster coating on each section, means for detachably connecting the wall sections together and a finish strip covering the joint between the sections and overlying the protecting strip on each section at the edge of the plaster coating.

5. In a cement finish refrigerator, the combination with a plurality of wall sections each comprising a skeleton framework filled with insulating material and provided with a coating of concrete, plaster or the like, a metal protecting strip inclosing the edge of the plaster coating for each section, means for detachably connecting the sections together to form a completed wall and angle shaped finish members at the corners of the refrigerator, said finish members overlying the protecting strip at the edge of the plaster coating.

In testimony whereof, I have signed my name to this specification.

HARRY H. REED.

120
